CLAIM

The ornamental design for ear plug core as shown and described.

DESCRIPTION

FIG. 1 is a first perspective view for ear plug core showing my new design;

FIG. 2 is a front view thereof, the rear and side views being identical to the front view;

FIG. 3 is a top view thereof;

FIG. 4 is a bottom view thereof;

FIG. 5 is a second perspective view thereof;

FIG. 6 is an enlarged view of Section B of FIG. 1; and,
FIG. 7 is a perspective view showing ear plug core in an environment of use.

The dash-dash broken lines in FIGS. 1 and 6 represent the bounds of the enlargements taken from FIG. 1 and forms no part of the claimed design. The dash-dash broken lines in FIG. 7 depicting an ear tip, illustrate environmental subject matter that forms no part of the claimed design.
